UNITED STATES PATENT OFFICE

2,403,160

GRINDING MACHINE

Stephen E. Woodbury, Beverly, Mass., assignor to
 Reid Brothers Company, Inc., Beverly, Mass., a
 corporation of Massachusetts

Application January 6, 1944, Serial No. 517,208

12 Claims. (Cl. 51—92)

1

This invention relates to grinding machines and consists in certain improvements in the starting and stopping mechanism therefor designed to increase the efficiency, precision and safety of such machines in operation and their convenience of control by the operator.

The invention is herein shown in its application to a surface grinding machine of the character more fully disclosed in my pending application Serial No. 500,078 filed August 26, 1943, which matured as Patent 2,390,978 on Dec. 11, 1945, and to which reference may be had for details of construction not herein shown. It will be understood, however, that the invention is not restricted to grinding machines of that or of any specific type but is of general application.

An important feature of the present machine consists in a single starting lever or handle movable for the two functions of engaging or disengaging a clutch interposed between the table and its motor and also for opening or closing a switch controlling the flow of current to the table motor.

In grinding machines as heretofore constructed, it is customary to provide a clutch in the train of mechanism for operating the table and to provide an off and on switch in the motor circuit. Heretofore the clutch and switch have been separate and distinct and have been arranged for separate operation, that is to say, the user has been obliged to throw the switch as one operation and then to shift the clutch as a separate and distinct operation. Under these conditions the table motor is often left idling at full speed while the clutch is disengaged. Moreover an objectionable shock occurs when the clutch is engaged with the motor running at full speed. The elimination of this shock is desirable for work where a high degree of precision is required. The present invention provides mechanism whereby the table motor is stopped by cutting off its operating current at approximately the same time that the motor is mechanically disconnected from the table. The operator does not have to perform an extra operation nor can he forget to turn off the table motor when changing to hand operation. With this end in view an important feature of my invention consists in a self-closing switch in the motor circuit which is arranged to be automatically opened whenever the starting handle is returned to its initial position in the course of its clutch disengaging movement. Means are also provided for detachably latching the starting handle in running position, that is to say, with the motor switch closed and mechanical connection established between the motor and the table

5 by engagement of the clutch. Further, the mechanism of my invention is preferably designed to insure closing of the motor circuit shortly before engagement of the clutch so that the clutch is engaged before the motor has acquired its full speed of rotation, thereby eliminating or largely reducing the shock caused by a more abrupt pick-up of the table operating mechanism.

10 These and other features of the invention will be best understood and appreciated from the following description of a preferred embodiment thereof, selected for purposes of illustration and shown in the accompanying drawings, in which—

Fig. 1 is a fragmentary view in perspective of the grinding machine,

Fig. 2 is a view in perspective of the driving mechanism unit,

Fig. 3 is a skeleton view in perspective of the controlling mechanism, and

15 Figs. 4 and 5 are wiring diagrams.

In its general organization the illustrated machine includes a box frame 10 from the rear side of which rises an upright column 11. The grinding wheel 12 together with its spindle and individual driving motor (not shown) are mounted for vertical adjustment in a slide carrier movable upon the column 11. In the top of the machine frame 10 are provided transverse ways in which rests the cross slide 13. The slide 13 is provided 20 with longitudinal ways in its upper face and in these slides the elongated work table 14 herein shown as equipped with a magnetic chuck 15. The work to be ground is clamped upon this chuck and fed back and forth beneath the grinding wheel 12.

An individual motor 17 is provided for imparting longitudinal movement to the table 14. This motor, its driven train and its controlling mechanism are organized as a unit and mounted upon 25 a panel 20 which is removably secured to the left hand side of the frame 10. The motor 17 is mounted externally on the panel 20 and directly connected to a reducing gear set enclosed in a casing 22 and supported by a bracket 21 formed 30 as a part of the panel. The out-put shaft 23 of the reducing gear carries the fast member 24 of a toothed clutch and with this cooperates a corresponding loose member 25 which is formed as part of a sleeve carrying a driving pinion 26. The loose member 25 of the clutch is controlled by 35 a forked shipper 27 carried by a shaft 37 disposed parallel to the shaft 23 and supported at one end in the bracket 21 and at the other in a second bracket 39 which projects inwardly from the panel 20. A coil compression spring 40 surrounds

the shaft 37 and tends always to push the shipper 27 toward the left as shown in Figs. 2 and 3 and so to disengage the clutch 24-25. When the shipper 27 is moved toward the right by the operator in opposition to the spring 40, the clutch is engaged and the driving pinion 26 set in rotation. The reduction in speed between the motor 17 and the out-put shaft 23 may be in the order of 7 to 1.

Rotation of the pinion 26 effects the longitudinal movement of the table 14 through chain and sprocket mechanism fully disclosed in my co-pending application but not herein illustrated since it forms no part of the present invention. However, it will be understood that whenever the pinion 26 is set in rotation the table 14 is thereupon moved longitudinally in a direction corresponding to the direction of rotation of the pinion. The motor 17 and the pinion 26 are reversed in direction at each end of the table movement by mechanism controlled by adjustable dogs on the table 14, one of which dogs 16 is shown in Fig. 1.

The starting handle 30 of the machine is mounted on a transverse shaft 31 journaled in the panel 20 and having a shouldered sleeve 32 pinned to its outer end. The handle 30 has a hub 33 in which is formed a shoulder arranged to engage with the corresponding shoulder in the sleeve 32 and so determine the initial position of the handle as shown in Fig. 2 while providing a limited angle of lost motion before the handle begins to turn the shaft 31 in its starting stroke. At its inner end the shaft 31 is provided with a downwardly extending arm 34 to which is pivotally attached a block 35. The block 35 is arranged to slide in vertical ways formed in one side face of a sleeve 36 which is fast upon the shaft 31 and to which the shipper 27 is connected. It will be apparent that as the starting handle is swung downwardly from its initial position, the sleeve 36 will be moved toward the right as will be seen in Figs. 2 and 3, the spring 40 compressed and the clutch 24-25 engaged when its teeth register with each other.

The arm 34 has a hub 41 surrounding the shaft 31 and from this hub projects upwardly a lug 42. A shouldered pawl 43, cooperating with the lug 42, is mounted upon a stud 44 projecting inwardly from the panel 20. A tension spring 48 tends always to swing the pawl 43 downwardly and to cause it to engage the lug 42 when the starting handle has been swung to running position, thus maintaining the machine in operation. A forked link 47 is pivotally connected to the free end of the pawl 43 and this engages at its lower end with an angular rod 45 projecting inwardly from the hub 33 of the starting handle. A tension spring 46 extends between the rod 45 and a pin on the panel 20 and tends always to swing the starting handle upwardly to its initial position determined by the shoulders of the hub 33 and the sleeve 32. The link 47 has the function of swinging the pawl 43 upwardly to an inoperative position and holding it in that position while the machine is at rest. When the starting handle 30 is swung downwardly, the rod 45 also moves downwardly and the link 47 thereupon permits the pawl 43 to engage the lug 42 as already explained.

The starting and stopping switch for the motor 22 is carried by a plate 50 mounted upon the inner face of the panel 20. The switch comprises a longitudinally movable bar 51 carrying two sets of spring contact members 52. These co-operate with corresponding sets of stationary contact members 53 disposed on opposite sides of

the bar. A spring 54 normally urges the bar 51 toward the left so as to close all four contacts 52-53. The inner end of the rod 45 is shaped to meet the left hand end of the bar 51 when the starting handle is restored to its initial position and thereby to displace the bar 51 toward the right against the compression of the spring 54, opening the contacts and cutting off power from the motor 22. On the other hand, when the starting handle is swung downwardly as shown in Fig. 3 the end of the rod 45 recedes from the bar 51 and its spring 54 is therefore permitted to close all the contacts and start the motor while the rod continues to move idly during the further movement of the starting handle.

From the foregoing description it will be apparent that the spring 46 holds the starting handle 30 normally in its initial position as shown in Fig. 2 with the clutch 24-25 disengaged and the switch bar 51 displaced toward the right and held in open-switch position. When it is desired to set the machine in operation, the operator has merely to swing the starting handle downwardly until the shaft 31 with its lug 42 is latched by the pawl 43. In this movement the starting switch is first permitted to close, by the retracting movement of the rod 45, and the driven shaft 23 is set in rotation together with the clutch member 24. Continued movement of the starting handle brings the end faces of the clutch members into contact. Immediately upon registering the teeth of the two clutch members the clutch is engaged and the table 14 set in motion. By this time the lug 42 has been turned to a position in which it can be latched by the pawl 43 and the machine will continue to operate until the starting handle is swung upwardly with the assistance of the tension of the spring 46. It will be understood, that, with the parts in the positions shown in Fig. 3, the spring 46 while tending to move the handle 30 upward, is resisted by the friction between the pawl 43 and the lug 42, with the result that the handle remains in the lower position shown until it is manually moved upward to disengage the pawl from the lug by means of the rod 45 and the link 47. At or about the instant of disengagement of the pawl 43 from the lug 42, the shoulder on the hub 33 of the handle engages the mating shoulder on the sleeve 32, thus enabling the handle in cooperation with the spring 40 to restore the parts to the relative positions shown in Fig. 2. The handle is then held in its upper position by the spring 46. It will be apparent that during this upward movement, the handle 30 effects disengagement of the clutch and opening of the switch.

A hand wheel 28 is fast to a short shaft journaled in bearings projecting from the front of the frame 10 and at its inner end this shaft has clutch teeth for engaging corresponding teeth on the pinion 26 when the latter is shifted by the handle 30 in disengaging the clutch 24-25. It will be seen, therefore, that when the pinion 26 is disconnected from its power driven chain of mechanism it is connected to the hand wheel 28 by which the table 14 may be then moved manually. The longitudinal reciprocations of the table 14 take place independently of the transverse position of the cross slide 13 in the machine. It will be understood that the machine includes automatic mechanism for effecting a cross feeding step before each traverse of the work beneath the grinding wheel 12.

In Fig. 4 is a wiring diagram showing a three phase motor 17 with the self-closing switch above

described included in its service circuit. In Fig. 5 a two phase motor 170 is shown with the same switch in its service circuit. In both these figures the bar 51 corresponds to the bar of the switch shown in Figs. 2 and 3, the movable contact points 52 correspond to the movable contact points carried by the spring arms of the bar 51, and the stationary contact points 53 correspond to the stationary contact points shown in Figs. 2 and 3. It will be noted that when the switch is open 10 the flow of current is cut off in two of the service wires in each diagram.

The sleeve 36, as shown in Fig. 3, is free to move toward the left until it brings up against the bracket 39 and when free to do so the spring 40 15 will accordingly hold the sleeve in contact with the bracket. This in turn determines the initial position of the arm 34, the shaft 31, the sleeve 32 and lastly the starting handle 30.

Having thus disclosed my invention and described in detail one desirable embodiment thereof, I claim as new and desire to secure by Letters Patent:

1. In a grinding machine having a reciprocating table and a motor for operating the table, a self-closing switch for controlling the motor, a clutch interposed between the motor and table, a spring for causing the clutch to disengage, and a single starting lever movable to oppose said spring and to release said switch so it will close prior to the engagement of said clutch.

2. In a grinding machine having a reciprocating table and a motor for operating the table, operating mechanism between the table and motor including a motor-driven shaft having interfitting clutch members thereon, a starting lever, a spring tending to disengage said clutch members and arranged to be compressed by said lever, a self-closing switch controlling the operation of said motor, and means controlled by said lever for closing said switch when the starting lever is moved to compress the clutch spring.

3. In a grinding machine having a reciprocating table, a motor and driving mechanism including a clutch between the motor and the table, a starting lever, a switch in the motor circuit, connections between said lever and switch, connections between said lever and clutch, operating first to cause closing of the switch and then to cause engagement of the clutch, and means for temporarily latching the said lever in running position.

4. In a grinding machine having a motor driven reciprocating table, driving mechanism for the table including a clutch and a motor operating circuit including a switch, a starting lever, means operated by movement of the lever in one direction for engaging the clutch and closing the switch, means operated by movement of the lever in the opposite direction for positively opening the switch, and spring means controlled by movement of the lever in the last said direction for disengaging the clutch.

5. In a grinding machine having a motor driven reciprocating table, driving mechanism for the table including a clutch and a motor operating circuit including a switch, a starting lever, means operated by movement of the lever in one direction for positively engaging the clutch, spring means controlled by movement of the lever in the said direction for closing the switch and means operable by movement of the lever in the opposite direction for effecting the disengagement of the clutch and the opening of the switch.

6. In a grinding machine having a reciproca-

tory table, a detachable driving and controlling unit comprising a panel, a motor mounted thereon, a driving train between the motor and table including a clutch, a spring for disengaging said clutch, a self-closing switch in the motor circuit carried by the panel, a shaft journaled in the panel and having a starting handle at its outer end, an angular rod movable with said shaft for opening said switch, and a shipper connected to the shaft and movable therewith to cause the clutch to engage.

7. In a grinding machine having a frame supporting a reciprocating table; a detachable panel having a motor mounted thereon, a driving train between the motor and table including a clutch, a spring tending normally to disengage said clutch, a motor circuit including a self-closing switch carried by the panel, a shaft journaled in the panel and having a starting handle in its outer end, connections movable with the shaft for positively opening said switch, a shipper connected to the shaft and movable therewith for engaging the clutch, and a hand wheel mounted in the machine frame and operatively connected to the said driving train whereby the table may be moved when the clutch is disengaged.

8. In a grinding machine having a reciprocating table and a motor for driving the same, a clutch interposed between the table and the motor, a switch for controlling the operation of the motor, and a single hand lever movable in one direction and having a lost motion connection for causing the switch to close and other connections for causing the clutch to engage after the motor has been started by the closing of the switch and being movable in the opposite direction for causing the switch to open and the clutch to disengage.

9. In a grinding machine having a reciprocating table and a motor for driving the same, a clutch interposed between the table and the motor, a switch for controlling the operation of the motor, a single movable hand lever, and a lost motion connection operable by a continuous movement of the hand lever in one direction to effect closing of the switch and other connections for subsequently effecting engagement of the clutch.

10. In a grinding machine having a reciprocating table and a motor for driving the same, a clutch interposed between the table and the motor, a switch for controlling the operation of the motor, a single movable hand lever, lost motion connections operable by a continuous movement of the hand lever in one direction to effect closing of the switch and other connections for subsequently effecting engagement of the clutch, and operable by a continuous movement of the hand lever in the opposite direction to effect disengagement of the clutch and subsequently opening of the switch.

11. In a grinding machine having a reciprocating table and a motor for driving the same, a clutch interposed between the table and the motor, a switch for controlling the operation of the motor, clutch operating means for effecting engagement and disengagement of the clutch, a hand lever having a lost motion connection with the clutch operating means whereby the hand lever serves after its lost motion movement in one direction to actuate the clutch operating means to effect engagement of the clutch, and means movable with the hand lever for effecting closing of the switch during the said lost motion

and prior to the said actuation of the clutch operating means.

12. In a grinding machine having a reciprocating table and a motor for driving the same, a clutch interposed between the table and the motor, a switch for controlling the operation of the motor, clutch operating means for effecting engagement and disengagement of the clutch, a hand lever having a lost motion connection with the clutch operating means whereby the hand lever serves after its lost motion movement in one direction to actuate the clutch operating means

to effect engagement of the clutch, means movable with the hand lever for effecting closing of the switch during the said lost motion and prior to the said actuation of the clutch operating means, an automatically acting latch for holding the clutch operating means in the clutch engaging position, and means operable by the lost motion movement of the hand lever in the opposite direction for disengaging the latching means to release the clutch operating means and permit clutch disengaging movement thereof.

STEPHEN E. WOODBURY.
